United States Patent Office

Des. 189,556
Patented Jan. 3, 1961

189,556

JAR

Howard C. Wolf, Baltimore, Md., assignor to McCormick
& Company, Incorporated, Baltimore, Md., a corporation of Maryland

Filed Nov. 20, 1957, Ser. No. 48,567

Term of patent 14 years

(Cl. D58—25)

Fig. 1

The dominant features of my design reside in the portions shown in full lines.

I claim:

The ornamental design for a jar, as shown and described.
